UNITED STATES PATENT OFFICE

167,381

TIRE

**Theron J. Thaden, Akron, Ohio, assignor to The
Goodyear Tire & Rubber Company, Akron,
Ohio, a corporation of Ohio**

Application November 3, 1951, Serial No. 17,271

Term of patent 14 years

(Cl. D90—20)

To all whom it may concern:

Be it known that I, Theron J. Thaden, a citizen of the United States, residing in Akron, in the county of Summit and State of Ohio, have invented a new, original, and ornamental Design for a Tire, of which the following is a specification, reference being had to the accompanying drawing, forming part thereof.

Fig. 1 is a perspective view of a tire, showing my new design; and

Fig. 2 is a fragmentary cross-section of the tire taken on line 2—2 of Fig. 1.

I claim:

The ornamental design for a tire, as shown.

THERON J. THADEN.
